THE NORRIS PETERS CO., WASHINGTON, D. C.

UNITED STATES PATENT OFFICE.

MARIA GERTRUDE DECIES, OF SLOUGH, ENGLAND.

HAIR-CURLER.

No. 905,799.

Specification of Letters Patent.

Patented Dec. 1, 1908.

Application filed April 11, 1908. Serial No. 426,460.

To all whom it may concern:

Be it known that I, Lady MARIA GERTRUDE DECIES, of Sefton Park, Slough, in the county of Buckingham, England, baroness, have invented certain new and useful Improvements 5 in Hair-Curlers, of which the following is a specification.

This invention has reference to and comprises improvements in and relating to the 10 construction of hair curlers of the class in which the hair is wound around one part or arm which is then secured by clipping or clamping to another part to hold it in position, and has for its object the production of 15 an ornamental hair curler which will not break or tear the hair of the user.

In order that others skilled in the art to which my invention relates may properly understand same, I have hereunto appended 20 one sheet of explanatory drawings in which

Figure 1 is a side view of the hair curler in its open position, Fig. 2 a similar view showing the hair wound on to the main arm, Fig. 3 also a similar view but showing the movable arm closed down and clamped in position, while Fig. 4 is a side view illustrating a modified construction. Fig. 5 is a plan corresponding to Figs. 1 to 3. Fig. 6 is a plan view drawn to a larger scale of a piece 25 of covered ribbon wire, with the covering partially broken away; Fig. 7 is a section of the wire on the line 7—7, Fig. 6, and Fig. 8 is a section on the line 8—8, Fig. 1, showing the covered wire ready for use.

35 Referring to these drawings:—In carrying this invention into effect or practice the hair curler is formed of tough flexible material covered with thin soft leather A secured by sewing, or by other equivalent material to 40 prevent damage to the hair and is constructed in two main parts as follows:—One part B consists of a short length of the material technically known as "ribbon wire" and commonly used by milliners and as shown in 45 Figs. 6 to 7, is composed of wires E of tough flexible metal in combination with a fabric of cotton or other fibrous material F. The length of ribbon wire is covered with leather A as shown particularly in Fig. 8 and has one 50 end C reverted or bent as shown in Fig. 1,

this end being capable of being bent to an angle and reverted as shown in Fig. 3 repeatedly as desired without breaking. This part B may however be reverted at both ends C and D, as shown by Fig. 4, if desired. The 55 other part or arm G consists of another length of the same material, or it may be of any flexible elastic or springy metal or material also covered with leather and secured to the part B by one end being secured to 60 the end D of the part B, as shown in Figs. 1 to 3 or it may be as shown in Fig. 4 beneath the reverted end D of the main part.

In use the reverted end C is opened and the arm G raised to the positions shown in Fig. 1. 65 The hair to be curled is then wound on to the part B, as indicated in Fig. 2, when the arm G is closed down on it and secured by the end C being closed down over the end of the arm as shown in Fig. 3. Otherwise the hair may 70 be wound on to the arm G which is afterwards closed down and secured by the reverted end C of the part B.

Instead of wire or metal plate the hair curler may be made of any suitable tough 75 flexible or elastic material, which will fulfil the desired conditions.

To give an ornamental appearance when in use rosettes I or loops of narrow ribbon are attached to each end, as shown in Fig. 5, but 80 these, of course, may be dispensed with if desired.

What I claim as my invention and desire to secure by Letters Patent is:—

1. Hair curlers composed of wire ribbon 85 covered with soft leather and formed in two parts secured together, substantially as set forth.

2. In hair curlers the combination of parts consisting of a length of ribbon wire covered 90 with soft leather with reverted ends and an arm of same material secured thereto substantially as set forth.

In testimony whereof I have signed my name to this specification, in the presence of 95 two subscribing witnesses.

MARIA GERTRUDE DECIES.
